SUPPORTING STRUCTURE

John B. O'Keefe, Chicago, and Celestine M. Igoe,
Crystal Lake, Ill.

Application December 4, 1951, Serial No. 259,766

15 Claims. (Cl. 155—124)

1

This invention relates to a structure for supporting children afflicted with cerebral palsy and the like, and more particularly to a table and chair combination suitable for such use.

Various table and chair combinations of this type have heretofore been proposed which require straps or ties to provide the necessary support for spastic children—those afflicted with cerebral palsy—while they are sitting in the chair. Furthermore because of the need for ties and straps, such combinations are frequently uncomfortable to the child and are awkward and clumsy to handle when seating or unseating the child.

It has been generally found that spastic children, when seated in a chair, have a normal tendency to cross their legs in an uncontrolled manner, thereby impairing their balance. The various chairs and chair combinations heretofore proposed have failed to satisfactorily overcome this difficulty without resorting to the use of straps and the like.

Thus it is one of the objects of this invention to provide a table and chair combination which will afford adequate, yet comfortable, support to a child afflicted with cerebral palsy and the like without the need for straps, ties, and the like.

It is a further object of this invention to provide a table and chair combination which enables the child to be seated and unseated without delay.

It is a still further object of this invention to provide a table and chair combination which will correct the tendency of a spastic child to cross his or her legs when in a sitting position and thereby materially assist the child in maintaining his or her balance.

It is a still further object of this invention to provide a table and chair combination for a spastic child which will not materially interfere with the freedom of movement of the child's arms and legs.

It is a still further object of this invention to provide a table top and leg-separating element which may be readily attached to conventional school type desks, tables, and chairs which are presently in use.

It is a still further object of this invention to provide a table and chair combination which is simple and compact in construction, effective in aiding the child to overcome his or her handicap, and is inexpensive to produce.

Further and additional objects will appear from the description, accompanying drawings, and appended claims.

2

In accordance with one embodiment of this invention, a table and chair combination is provided comprising an upright table support, an upright chair support operatively connected to the table support and mounted in spaced relation with respect thereto, and a leg-separating element disposed intermediate said supports and operatively connected to one of said supports and adjustable with respect thereto.

For a more complete understanding of this invention reference should be made to the drawings wherein:

Figure 1 is a side elevational view of a table and chair combination showing one form of leg-separating element;

Fig. 2 is a top plan view of Fig. 1;

Fig. 3 is a left end view of Fig. 1;

Fig. 4 is an enlarged perspective view of a portion of the table showing the top thereof disengaged;

Fig. 5 is a fragmentary sectional view taken along line 5—5 of Fig. 1;

Fig. 6 is a fragmentary side elevational view of a table and chair combination showing the leg-separating element in an inoperative position;

Fig. 7 is similar to Fig. 1 but showing a second form of leg-separating element;

Fig. 8 is a fragmentary sectional view taken along line 8—8 of Fig. 7;

Fig. 9 is similar to Fig. 1 but showing another form of leg-separating element;

Fig. 10 is a fragmentary sectional view taken along line 10—10 of Fig. 9 and

Fig. 11 is an enlarged fragmentary sectional view taken along line 11—11 of Fig. 7.

Referring now to the drawings, and more particularly to Figs. 1-3, a table and chair combination 11 is shown for use primarily by children afflicted with cerebral palsy or other forms of paralysis. The combination comprises a table 12, a chair 13 spaced from said table, and a leg-separating element 14 disposed intermediate the table and chair.

The table 12 may be of conventional design and comprises an upright support or standard 15 and a compartment 16 mounted for swivel adjustment on the upper end thereof. The compartment 16 may be locked in various positions of swivel adjustment relative to the support 15 by a locking collar 16' which embraces the latter. The compartment 16, as seen more clearly in Fig. 4, has one side, thereof, adjacent the chair 13, open so as to enable books, etc. to be stored therein. Slidably mounted on the upper side of compartment 16 is a table top 17 which

is inclined upwardly a slight amount from the chair 13. The top 17 is substantially flat and rectangular or square in shape, as seen in Fig. 2, and has the outer edge thereof provided with an upturned molding 18. If desired, the top 17 may be constructed of slate or any other similar type of material so that the child may practice drawing or writing directly on the top with chalk and the like. The molding 18 serves to prevent pencils, chalk, or any other loose articles from being accidentally knocked off the top by the child. The edge of the top 17, adjacent the chair 13, is provided with a cutout portion 20 which is substantially semicircular in shape and is adapted, when the top is moved to its full rear position, as shown in full lines in Fig. 1, to partially embrace the trunk of the child seated in the chair. Thus the upper portion of the child is supported by the top 17, and thereby materially assists the child in maintaining his balance while sitting in an upright position. A lock cooperating with the compartment and top, not shown, may be provided, if desired, for locking the latter in its full rear position.

Mounted on the underside of top 17 are a pair of depending guide members 21a and 21b which are arranged in spaced parallel relationship with respect to one another and extend substantially the entire length of said top. The guides, when the top is assembled on the compartment, are adapted to slidably engage a pair of tracks 22a and 22b, respectively, which are formed on the upper edge of compartment 16, as seen more clearly in Fig. 4. An upturned flange 23 is provided along the upper front edge of the compartment 16, intermediate guides 21a and 21b, which is adapted to prevent fingers from being placed between the top and the compartment when sliding the former into and out of position.

The chair 13 may be of conventional design and is provided with an upright support 24 which has one leg 25 thereof integrally connected to one leg of the table support 15. Swivelly mounted on the upper end of support 24 is a seat 26 which is provided with an upwardly extending back rest 27. The seat may be locked in various positions of swivel adjustment by a locking collar 26' which embraces the support 24. The back rest is adapted to be disposed in close proximity with the cutout portion 20 of top 17 when the latter is in its full rear position. Thus the cutout portion 20 and back rest 27 cooperate with one another to effect almost complete enclosing of the trunk of the child.

Disposed intermediate the supports 15 and 24 is the leg-separating element 14, one form of which is shown in Figs. 1-3, 5 and 6, which comprises a body piece 28 which is hingedly mounted at point 30 to the underside of the front edge of seat 26. The periphery of the underside of the body piece 28 is curved, as seen in Figs. 1 and 6, so as to enable the leg-separating element 14 to be swung down to its inoperative position. The body piece 28 is locked in various positions of pivotal adjustment by a ratchet 32 and pawl 33 combination. The ratchet 32 is secured to one side of the element 14 adjacent the hinge 30 by screws 32' or any other suitable means. The serrated edge of the ratchet 32 is engaged by pawl 33 which is rigidly mounted on a rotatable shaft 34, as seen more clearly in Fig. 5. The shaft 34 is supported in a bearing bracket 36 and has one end of the shaft 34 extending beyond the bracket 36 and terminating in a handle 35. The handle is disposed adjacent the side of

the seat 26 to facilitate manipulation thereof when removing the child from the seat. The handle 35 effects rotation of the shaft 34 in a counterclockwise direction, as viewed in Fig. 1, and effects disengagement of the serrated edge of the ratchet 32 by the pawl 33, whereupon the element 14, due to its unbalanced condition, assumes its inoperative position as seen in Fig. 6.

Bearing bracket 36 which supports shaft 34 is substantially U-shaped and is secured to the underside of the front edge of the seat 26. Suitable braces 37 are provided for lending support to the bracket 36 as seen in Fig. 1. A portion of the shaft 34 is embraced by a coil spring 38 and effects biasing of the shaft in clockwise direction, as viewed in Fig. 1, so as to insure positive meshing between the ratchet 32 and the pawl 33. A suitable cutout portion 40 is provided in the body piece 28 to accommodate the bracket 36 and the pawl 33, when the leg-separating element 14 assumes its inoperative position.

A second form of leg-separating element 41 is shown in Figs. 7 and 8, comprising a substantially flat rectangularly-shaped body piece 42 which is hingedly mounted to the table support 15 by a sleeve bracket 43, as seen in Fig. 7, which embraces said support. The sleeve bracket enables the body piece 42 to be swung about support 15 as an axis in either a clockwise or counterclockwise direction through an arc of approximately 90° from the position of the body piece, shown in full lines in Fig. 8. Mounted on the upper edge of body piece 42 adjacent the underside of seat 26, is a locking device 44, which comprises a latch housing 44', a catch 45, and a spring biased latch 46. The latch housing 44' is mounted on one side of the body piece 42 and the catch 45 is mounted on the centerline of the underside of the seat 26. The latch 46 is adapted to seat within an opening 47 formed in catch 45, when the body piece 42 is moved to its operative position, which is in substantially coplanar relation with the supports 15 and 24. A knob 47' is provided on latch housing 44' which, upon turning, effects disengagement of the latch 46 from the catch 45. The latch 46, which, as heretofore mentioned, is spring biased to an extended position, readily engages one or the other of the tapered sides 49 of catch 45, see Fig. 11, and is depressed thereby, when the body piece 42 is swung to its normal operative position, until it comes in registration with the opening 47 whereupon, it will seat therein and hold the separating piece 42 in said operative position.

Figs. 9 and 10 show the body piece 42 hingedly connected to the chair support 24 instead of support 15 by a sleeve bracket 48. In other respects the body piece 42 and the locking device, shown in Figs. 9 and 10, are of the same construction as that shown in Figs. 7, 8 and 11.

When seating the child in the table and chair combination shown in Fig. 1, the table top 17 is pushed forward to the position shown in dotted lines, and the ratchet and pawl are disengaged by rotating the handle 35 in a counterclockwise direction, enabling the element to assume its inoperative, or down, position. The child is then placed in the seat so that his or her legs straddle the element 14. The element is then raised to normal operating position and the table top is pulled back to its full rearward position, as seen in Fig. 2, whereupon the trunk of the child is held between the table top and back rest of the chair.

When the modified form of leg-separating ele-

ment 41, as shown in Figs. 7 and 8 or Figs. 9 and 10, is used the body piece 42 is pivoted about either support 15 or 24 a sufficient amount so as to enable the child to be readily placed on the seat behind the compartment 16. While the child is so positioned, the body piece 42 is swung back to its normal position until the latch 46 seats itself in the opening 47 formed in the catch 45. One leg of the child is then lifted over the body piece 42 so that it is straddled by the legs of the child.

Thus it will be seen that a table and chair combination has been provided which is particularly suited for crippled children, afflicted with cerebral palsy and the like, and provides adequate, yet comfortable, support for such children without the need for straps, ties and the like. Furthermore, the table and chair combination enables the child to be readily seated or unseated and also is helpful in aiding the child to learn how to maintain his or her balance when seated. While the leg-separating elements and slideable table top are shown used on a table and chair combination, it is to be understood, of course, that they are not limited to such structures, but may be used on tables or chairs which are entirely separate from one another. Furthermore, such elements or table tops may be incorporated in tables, chairs, or combinations thereof which are presently in use.

Further modifications of the invention may be made and it is contemplated by the appended claims to cover any such modifications as fall within the true spirit and scope of this invention.

We claim:

1. A structure of the class described comprising an upright support having a member mounted on the upper end thereof and angularly disposed with respect thereto, and an upright leg-separating element disposed beneath said member and operatively connected to said support for movement relative thereto.

2. A structure of the class described comprising an upright support having a member mounted on the upper end thereof and angularly disposed with respect thereto, and an upright substantially flat leg-separating element disposed beneath said member and operatively connected to said support for pivotal movement relative thereto.

3. A structure of the class described comprising an upright support having a member mounted on the upper end thereof and angularly disposed with respect thereto, and a substantially flat leg-separating element disposed beneath said member and hingedly connected to said support; said element being disposed in substantially coplanar relation with respect to said support.

4. A structure of the class described comprising an upright support having a member mounted on the upper end thereof and angularly disposed with respect thereto, a leg-separating element disposed beneath said member and operatively connected to said support for pivotal movement relative thereto, and means cooperating with said element for holding same in one position of pivotal adjustment; said element being disposed in substantially coplanar relation with respect to said support.

5. A structure of the class described comprising an upright table support, an upright chair support operatively connected to said table support and in spaced relation with respect thereto, a leg-separating element disposed intermediate

said supports and operatively connected to one of said supports for pivotal movement thereto, and means mounted on said element and cooperating with one of said supports for holding said element in one position of pivotal adjustment and in coplanar relation with respect to said supports.

6. A structure of the class described comprising an upright table support, a member slidably mounted on the upper end of said table support and angularly disposed with respect thereto, an upright chair support operatively connected to said table support and in spaced relation with respect thereto, and an adjustable leg-separating element operatively connected to one of said supports and disposed intermediate said supports and adapted to assume a coplanar relation with respect thereto.

7. A structure of the class described comprising an upright table support, a member slidably mounted on the upper end of said table support and angularly disposed with respect thereto, an upright chair support operatively connected to said table support and in spaced relation with respect thereto, a seat mounted transversely on the upper end of said chair support, and an upright leg-separating element disposed intermediate said supports and in coplanar relation therewith beneath said seat and pivotally connected to one of said supports.

8. A structure of the class described comprising an upright chair support, a seat mounted on the upper end of said support and provided with an upwardly extending back rest, an upright table support operatively connected to said chair support and disposed in spaced relation with respect thereto, a substantially flat member slidably mounted on the upper end of said table support and angularly disposed with respect thereto for movement toward and away from said back rest, and an upright leg-separating element operatively connected to one of said supports and disposed intermediate said supports and in coplanar relation therewith.

9. A structure of the class described comprising a substantially flat chair seat and a leg-separating element adjustably mounted on the underside of said chair seat for movement in a plane substantially perpendicular with respect to the plane of said chair seat.

10. A structure of the class described comprising an upright chair support having a substantially horizontal seat mounted on the upper end thereof, an upright leg-separating element pivotally mounted on the underside of said seat for movement in an upright plane, and means for holding said element in various positions of pivotal adjustment.

11. A structure of the class described comprising a chair seat and a leg-separating element adjustably mounted on the underside of said chair seat and extending forwardly and downwardly from said chair seat; said element being adjustable relative to said chair seat in a plane substantially perpendicular with respect thereto.

12. A structure of the class described comprising an upright chair support, a seat mounted transversely on the upper end of said support, an upright leg-separating element pivotally mounted on said support and disposed beneath said seat and extending forwardly thereof, and means cooperating with said seat and element for locking the latter in one position of pivotal adjustment.

13. The structure recited in claim 12 in which

the upright leg-separating element extends substantially the full height of the chair support.

14. A structure of the class described comprising an upright table support, a table top mounted on the upper end of said support and angularly disposed with respect thereto, an upright leg-separating element disposed beneath said top and pivotally mounted on said support and extending outwardly therefrom, and means cooperating with said element for locking the latter in one position of pivotal adjustment. 10

15. A structure of the class described comprising an upright chair support, a seat mounted transversely on the upper end of said support and having an upwardly extending back rest, an upright table support operatively connected to said chair support and in spaced relation with respect thereto, a table top slidably mounted on the upper end of said table support and angularly disposed with respect thereto for movement toward 20

and away from the back rest of said seat, said table top having the edge thereof adjacent said back rest provided with a body embracing portion, and an upright leg-separating element positioned intermediate said supports and incoplanar relation therewith and operatively connected to one of said supports.
